UNITED STATES PATENT OFFICE

113,443

DESIGN FOR A COMBINED DISPLAY CONTAINER AND SUPPORTING BASE FOR PERFUME BOTTLES OR SIMILAR ARTICLES

Joseph S. Stein, Chicago, Ill., assignor to Lucien Le Long, Inc., Chicago, Ill., a corporation of Illinois

Application August 25, 1938, Serial No. 79,556

Term of patent 7 years

To all whom it may concern:

Be it known that I, Joseph S. Stein, a citizen of the United States and a resident of the city of Chicago, in the county of Cook and State of Illinois, have invented a new, original, and ornamental Design for a Combined Display Container and supporting Base for Perfume Bottles or Similar Articles, of which the following is a specification, reference being had to the accompanying drawing, forming a part thereof.

On the drawing:

perfume bottles or similar articles showing my new design, with the cover elevated slightly above the base.

I claim:

The ornamental design for a combined display container and supporting base for perfume bottles or similar articles, as shown.

JOSEPH S. STEIN.
